STOVE

Frank G. Riordan, Spokane, Wash., assignor of one-half to Louise E. Burchett, one-tenth to Charles Burchett, one-tenth to Clarence Burchett, one-twentieth to George Burchett, and one-fifth to Irwin Enos, all of Spokane, Wash.

Application August 18, 1936, Serial No. 96,668

2 Claims. (Cl. 126—67)

This invention relates to a stove, and more particularly to a stove of the drum type used in small buildings or to heat one room of a building.

One object of the invention is to provide a stove 5 wherein the fire box, ash pit and the heating drum are enclosed in a casing through which air passes about the drum and becomes heated as it passes upwardly through the casing from entrances near the bottom thereof to an outlet consisting of a grating at the top of the casing.

Another object of the invention is to so form the drum portion of the stove that it will have a large area from which heat is to radiate and warm the air moving upwardly through the casing.

15 Another object of the invention is to provide improved means for directing hot gases and other products of combustion upwardly from the fire box through the drum and thus cause the walls of the drum to be highly heated.

20 It is another object of the invention to provide an improved type of head or upper end portion for the drum, this portion serving to connect the drum with the smoke pipe and being so constructed that passage of products of combustion 25 will be retarded and the upper portion of the drum caused to be very hot.

The invention is illustrated in the accompanying drawing, wherein

Figure 1 is a perspective view of the improved 30 stove.

Figure 2 is a sectional view taken vertically through the stove along the line 2—2 of Figure 1.

Figure 3 is a sectional view taken transversely through the stove along the line 3—3 of Figure 1.

35 This improved stove has a casing 1 which may be formed of sheet metal or any other material desired and is supported by a base 2 having floor engaging legs 3 to support it in an elevated position. The top 4 of the stove is supported upon the upper edges of walls of the casing and is removable therefrom so that access may be had to the interior of the casing in order to install the heating drum or to clean or repair the same when necessary. Slots are formed 40

45 at the top as shown in Figures 1 and 2, thereby providing a grating 5 through which hot air may pass out of the casing into a room to be heated. The air enters the casing near the bottom thereof through inlets 6 provided in each side wall of the casing and also in the back wall thereof, if so desired.

50 Within the casing is mounted a heating unit formed of cast metal and having a lower section 7 and an upper section or drum 8. The heating unit is of appreciably less dimensions than the

casing, as shown in Figures 2 and 3, thus providing space 9 about the heating unit through which the air passes as it moves upwardly through the casing. The lower section carries a grate 10 defining a fire box 11 and an ash pit 12 and in order 5 to permit access to the same the front wall of the casing is provided with a fire door 13 and an ash door 14.

The upper section or drum 8 of the heating unit is of a special formation and has its opposed side walls crimped, as shown in Figure 2, to divide the drum into superimposed sections 15 provided with tapered side portions having outwardly converging upper and lower wall portions 16 and 17. A deflector plate 18 is mounted in 15 the fire box under the restricted entrance at the lower end of the drum and spreader plates 19 are mounted in the sections 15 of the drum with portions extending into the tapered side portions thereof. By providing the plates 18 and 19, the 20 gases and other products of combustion will be forced to pass through all portions of the drum as they move upwardly through the same and the walls of the drum will be highly heated. The 25 converging wall portions 16 and 17 provide the drum with a large area from which heat radiates into the space 9 between the drum and walls of the casing 1 and, therefore, air moving upwardly through this space will be highly heated and pass 30 out through the grating as very hot air. At its upper end, the drum is formed with a head 20 having its upper wall 21 crimped to provide portions corresponding to the extensions of the 35 chambers of the drum and the lower wall 22 of the head is extended, as shown at 23, to provide a deflector which extends across the outlet 24 at the upper end of the drum and causes the products of combustion to enter the head 20 at the inner end thereof and then move through 40 the head towards the flue 25 which projects outwardly through a wall of the casing and is adapted to be connected with a smoke pipe leading to a chimney. It should be noted that the crimps of the upper wall of the head extend downwardly to 45 such an extent that they terminate in close proximity to the lower wall 22 of the head. This tends to retard quick passage of the smoke and other products of combustion through the head and the walls of the head will be highly heated and assist 50 in warming the air as it approaches the outlet at the top of the stove.

I have, therefore, provided a hot air stove which is of simple construction and very efficient in its 55 operation besides being of neat appearance.

Having thus described the invention, what is claimed as new is:

- 5 1. In a stove, a casing having an air outlet at its top and means for admitting air adjacent its bottom, and a heating unit in said casing comprising a lower section and an upper section, a grate in the lower section defining a fire box and an ash pit, the upper section defining a drum having an inlet at its bottom opening into the fire box and an outlet at its top, and a head extending across the top of said drum and having a flat bottom wall extended across the outlet of the drum to provide a baffle, the top wall of the head being crimped transversely to provide depending portions terminating adjacent the flat lower wall of the head and retarding passage of products of combustion through the head.
- 10 2. In a stove, a casing having an air outlet at its top and means for admitting air adjacent its bottom, and a heating unit in said casing comprising a lower section and an upper section, the

lower section providing a fire box and the upper section constituting a heating drum having a restricted opening at its bottom establishing communication with the fire box, opposed walls of said drum being crimped inwardly transversely of the 5 drum to provide the drum with superimposed sections having tapered end portions formed by outwardly converging crimped portions of the walls, and a head at the top of said drum extending transversely across the same and terminating in 10 a smoke flue projecting through a wall of the casing, said head having a flat bottom wall projected inwardly across an opening between the head and the upper end of the drum, and the top wall of the head being crimped transversely 15 to provide downwardly converging wall portions terminating adjacent the flat lower wall of the head and retarding passage of products of combustion through the head.

20 FRANK G. RIORDAN.
